UNITED STATES PATENT OFFICE.

GEORGE DOUTNEY, OF BROOKLYN, NEW YORK.

SAFETY ENVELOPE.

Application filed December 20, 1921. Serial No. 523,734.

To all whom it may concern:

Be it known that I, GEORGE DOUTNEY, a citizen of Canada, and a resident of the city of New York, borough of Brooklyn, in the county of Kings and State of New York, have invented a new and Improved Safety Envelope, of which the following is a full, clear, and exact description.

This invention relates to envelopes and particularly to envelopes which cannot be opened without being mutilated and has for an object to provide a structure which is extremely simple but easily manufactured and which may be easily closed.

Another object of the invention is to provide an envelope in which a hook and pocket structure is used for locking the flap closed, the arrangement being such that reinforcing and retaining tabs co-act with the hook for holding the same in proper operative position.

A further object of the invention is to provide an envelope in which there is provided not only a hook lock but a locking body section arranged in such a manner as to prevent extraction of any of the contents while the lock is properly functioning.

In the accompanying drawings—

Figure 1 is a rear view of an envelope constructed according to the present invention.

Figure 2 is a rear view of the envelope shown in Figure 1 but with the flap shown in an open position.

Figure 3 is a fragmentary view looking at the pocket shown in Figure 2 from the opposite direction.

Figure 4 is a sectional view through Figure 1 approximately on line 4—4, the same being on a greatly enlarged scale.

Figure 5 is a plan view of the blank used in forming the envelope shown in Figures 1 and 2.

Figure 6 is a plan view of a blank of the pocket shown in Figure 3.

Figure 7 is a perspective view of the pocket formed from the blank shown in Figure 6.

Figure 8 is a blank of an envelope which shows a slight modified form to that illustrated in Figure 5.

Figure 9 is a fragmentary view of the blank shown in Figure 1 illustrating how the pocket will appear when folded.

Figure 10 is a front view on a slightly

enlarged scale of a modified form of pocket to that shown in Figure 7.

Figure 11 is a section through Figure 10 approximately on line 11—11, the same being on an enlarged scale.

Referring to the accompanying drawings by numeral, 1 indicates a blank which is formed with a front or body 2 (Fig. 5) which is integral with a back 3 of substantially the same size as the body 2. Side flaps

4 and 5 extend from the body 2 for the full width of the body for a short distance, each of said flaps however, being cut away at 6 to present restricted tongues or extensions

7. These restricted tongues or extensions overlap as shown in Figure 2 and are held together by suitable adhesive as well as held to the back 3 by adhesive. The back 3 is provided with a slit or small slot 8 through

which the tongue 9 extends when the envelope is folded as shown in Figure 1 ready for mailing. Arranged on the inner surface of the back 3 is a pocket 10, which pocket is formed as shown in Figure 6, namely,

with a central section 11 and two side sections 12 and 13 which when folded over the section 11 will present a structure as shown in Figure 2, said folded members 12 and 13 being held together by suitable adhesive.

It will be noted that a flattened tubular structure 14 is produced by this folding action and a supporting projection 15, which supporting projection is adapted to receive a metallic staple 16 which extends through the overlapped extension 7 and through the projection 15. The pocket 10 is thus arranged so that the upper end of the flattened tubular structure 14 will register with the slot 8 so that when the tongue 9 is inserted as shown in Figures 1 and 4, said tongue together with the hook ends 17 and 18 will project not only through the slot but through the tubular portion 14 of the pocket. The hook ends 17 and 18 are part of the metallic hook 19 which is made of spring

wire preferably and which is arranged with spring arms or legs 20 and 21 connected by the cross bar 22 which cross bar is rigidly clamped in place by a metallic staple 23 similar to the staple 16. It will be noted that the tongue 9 is part of the closing flap 24 of the envelope and said closing flap is notched at 25 and 26 whereby reinforcing flaps 27 and 28 are provided, said flaps being

folded over the tongue 9 and secured thereto

by suitable adhesive as well as the staple 23. This will reinforce the tongue 9 and cause the flaps 27 and 28 to in effect become part of the tongue. By providing the hook 19 5 and associated parts including the locking pocket 10, the closing flap 28 cannot be opened either by an unauthorized or an authorized person without tearing after the same has once been properly closed as 10 shown in Figure 1.

It will be noted that the wire forming the hook ends 17 and 18 is bent back upon itself to present rounded members which will readily pass into the flattened tubular portion 14 of pocket 10 and be forced toward each other until they reach the end whereupon they will snap outwardly as illustrated in Figure 1. After this has been done the tongue and associated parts cannot be removed without tearing or mutilating the envelope. It is, of course, understood that the flap 24 is provided with adhesive in the usual manner so that in addition to the lock provided, the flap is held closed by adhesive. 25 By providing the staple 16 as described and constructing the flaps 4 and 5 and the back 3 as shown in Figure 5, no one can steam the envelope open nor can they open it otherwise without destroying certain parts. If 30 the adhesive 29 and 30 was steamed loose, a person's hand or an instrument of some kind might be forced upward between the outside of the back 3 and the inner surface of the flaps 4 and 5 but the hand or instrument could not move over the upper edge of 35 the back 3 to the contents without tearing certain parts of the envelope.

In Figures 8 and 9 will be seen a modified form of the invention in which the blank 1' 40 is identical with blank 1 except that the extension 7 on flap 5 is provided with an integral projection 11' similar to the portion 11 of the blank shown in Figure 6. The integral projection is provided with integral 45 sections 31 and 32 which complete the pocket when folded as shown in Figure 9 and the section 32 has a supporting projection 15' through which the staple 16 may be passed when the envelope is complete or ready for 50 use. The hook associated with tongue 9 acts as means for positively locking the tongue and closing flap in a closed position when properly positioned but to prevent any loose motion and to provide the usual sealing action, preferably adhesive is arranged on the opposite surface of the tongue to that shown in Figure 2 so that when it is inserted into the pocket, but properly moistened before 55 said insertion, it will adhere to the pocket and thereby assist in preventing disengagement of the hook.

Figures 10 and 11 show a slight modified form of pocket in which the front wall of the pocket section 14' is corrugated. This 60 corrugation is intended to expedite the in-

sertion of the tongue 9 by reason of normally holding the pocket slightly open.

The invention has been shown as embodied on an ordinary paper envelope but it will be understood that it might be embodied on an envelope made from linen, combination of linen paper, wooden containers, metal, fibers or other material or any other suitable combination thereof. The word "envelope" wherever used herein is to be understood to 75 embrace a container of any nature known by any name whatsoever and made from paper, wood, metal or any other material or combination of materials.

What I claim is:

1. A safety envelope formed from a blank having a body, a back of the same size as the body provided with a slit therein, end flaps adapted to be folded over said back, a closing flap formed with a tongue adapted to be extended through said slit, a pocket arranged interiorly of said back adjacent the slit so that when the closing flap is closed and the tongue projected through said slit it will be projected into said pocket, a hook carried by said tongue adapted to snap over the lower edge of said pocket when the tongue has been inserted fully, a metal staple for securing said hook in place, and a metal staple for connecting said end flaps, said back and said pocket together adjacent said slit.

2. In a safety envelope of the character described, a locking tongue comprising a projecting portion having a pair of overlapping flaps diagonally placed thereon and secured thereto, a hook carried by said tongue and a staple extending through said tongue, said overlapping flaps and over part of said hook for rigidly securing the various members rigidly together.

3. In a safety envelope of the character described, a closure section of the envelope, a closing flap therefor formed with a pair of converging notches at the center, said notches being spaced apart whereby a tongue will be provided, the material removed from said flaps for forming said notches being folded against said tongue, a hook member carried by said tongue, and means for rigidly securing said hook member and the folded material rigidly together.

4. In a safety envelope, a body portion formed with a front and back substantially of the same size and shape, the front being provided with a flap at each side formed with restricted end sections adapted to overlap each other when the flaps are folded on the body, a tongue receiving element disposed inwardly of the envelope, a staple securing said back, tongue receiving element and flaps together, said back being formed with a slot substantially in line with the upper edge of said tongue receiving element, a closing flap on the body, and means on the

closing flap adapted to pass through said slot and tongue receiving element and engage the lower edge of said tongue receiving element to permanently lock the closing flap to the back.

5. In a safety envelope, a blank formed with a body having a back section, a closure flap and a pair of end flaps, one of said end flaps being formed with an extension adapted to present a pocket when folded, said back section having a slot which is disposed in

line with the upper edge of said pocket when the parts are folded, a tongue member forming a part of said closure flap, resilient means secured to said tongue member, said tongue member and the resilient means being adapted to be inserted through said slot in said pocket so as to permit the resilient means to engage the lower edge of said pocket and thereby permanently lock the envelope. 15

GEORGE DOUTNEY. 20
